WELTING AND SHOEMAKING THEREWITH

Pearl C. Arnold, West Hanover, Mass., assignor,
by mesne assignments, to Barbour Welting
Company, Brockton, Mass., a co-partnership
composed of Perley E. Barbour, Walter G. Bar-
bour, and Richard H. Barbour

Application April 6, 1933, Serial No. 664,742

17 Claims. (Cl. 12—142)

This invention relates to the manufacture of
welting for incorporation in shoes having a short
upper, i. e. an upper so cut that it has no excess
margin that may be overlasted to lie under the
5 insole.

The object of this invention is to improve welting
of the type having a pair of edge flaps within
which the short upper is secured, by the addition
10 of a flange-like lasting allowance attached
to the welt through which the welt may be ex-
actly located at the edge of the insole and firmly
secured beneath the insole. Those skilled in the
art will recognize from the following description
15 that the novel welting may be applied completely
around a short shoe upper by a lapped joint, or
it may be applied only to the forepart of the upper
by butting and tucking in the ends as in
Goodyear work. The term "shoe upper" herein is
20 to be so understood. The lasting allowance on
the welting is preferably, but not necessarily, an
integral part of the strand from which the welting
is prepared and may be provided in several
ways as will hereinafter appear.

Accordingly this invention comprises welting of
25 the type described improved by the provision of
lasting allowance, the process of its manufacture,
and its incorporation in shoes of the kind having
a short upper, all as hereinafter described and
then particularly pointed out in the appended
30 claims.

The invention will best be understood by refer-
ence to the accompanying drawing in which:

Figure 1 shows a portion of a strand of grain
leather used as a blank;
35 Fig. 2 shows the welting strand of Fig. 1 split
twice at one edge to produce two upper embrac-
ing flaps and a lasting allowance flange;

Fig. 3 shows a variation of Fig. 2 in that both
edges of the strand are split for the purpose
40 stated;

Figs. 4 and 5 show how the welting strands of
Figs. 2 and 3, respectively, may be manipulated
while securing a welt to a short upper; and

Figs. 6 and 7 show sections of a shoe in which
45 the welts of Figs. 2 and 3, respectively, have been
incorporated.

In the following description the manufacture
and use of the welting of this invention will, for
simplicity, be confined to the processing of grain
50 leather, but it should be distinctly understood
that the usefulness of this invention is not
limited to leather because any suitable welting
material may be processed and used in like man-
ner; nor are dimensions given because they vary
55 greatly with the size and kind of shoe for which

the welting is made. The general field of usefulness
of the welting includes children's, growing
girls', misses', little gents' and boys' shoes; work
shoes for all ages; and sport shoes, particularly
of the serviceable type.

In the embodiment of the invention shown in
Figs. 2, 4 and 6 a grain leather strand 10 is split
twice transversely through one edge producing a
grain faced flap or flange 12 of reasonable weight
(according to the weight of the original strand), 10
an adjoining or central flesh flap or flange 13
preferably of lighter weight, and a second flesh
flap or flange 14 preferably of substantially the
weight of the grain faced flap. The grain face
of the strand 10, along the line of joinder of the 15
welt extension 15 and the slitted margin, may be
scored as at 16 to assist in folding or turning the
upper two flaps 12 and 13 upward parallelly relative
to the welt extension.

The lower edge of the shoe upper 18, that is 20
cut too short to overlant and which may have
merely its forepart short or may be short
throughout its periphery, is laid between the flaps
12 and 13 and secured to the welt, conveniently
by stitching. When incorporated in a shoe the 25
upper-embracing flaps stand substantially per-
pendicular to the plane of the welt extension 15
and in folding these flaps upward the grain faced
flap slides upward on the contiguous flesh flap.
In order to preserve a flat grain or to prevent 30
buckling, the flaps may be turned upward before
securing the upper as shown by Fig. 4. Also the
flange 14, which provides a lasting allowance, is
bent inward at this stage to a reversed position so
that the upper and upper-embracing flaps may 35
lie flat on the bed of a sewing machine. Ordinarily
the securement is by stitching in a Singer,
Puritan or other suitable dry thread sewing ma-
chine, one or more rows of stitching 28 being
used as may be desired. If the short upper is 40
provided with a lining 22 as is preferable in shoes
having this novel welt, the lining, if of the usual
length permitting lasting in under the insole,
merely hangs down loosely (see Fig. 4) in front
of the bed of the sewing machine while the welt 45
is being stitched to the upper.

The welted upper is then assembled on a last
with an insole 24. At this stage the extension 15
is outturned and the flange 14 extends inwardly
therefrom so that the latter may be used as a 50
lasting allowance if hand lasted, being seized by
the pincers and drawn over the insole and the
excess margin of the lining, or being wiped in
over the insole if lasted by a bed type machine.
The overlanted lining and welt flange 14 may be 55

secured to the insole by cement or by any suitable type of fastener. Littleway process staples are illustrated in Fig. 4. After lasting, the shoe is bottomed with an outsole 26 of any desired material and secured in any suitable manner as by an outseam 28. Later shoemaking steps may be as usual.

In the embodiment of the invention shown in Figs. 3, 5 and 7 the strand 10^a is split at one edge to form the grain faced and flesh flaps 12^a and 13^a adapted to embrace the scant upper 18^a but the lasting allowance flange 14^a is split in a lower plane (Fig. 3) from the opposite edge of the strand, being formed from the lower portion of the flesh below the welt extension 15^a. In stitching, as at 20^a, the flaps 12^a and 13^a may be turned upward as hereinbefore described, and with this form of the welt the lasting allowance flange 14^a naturally lies out of the way of the stitch-forming mechanism. Assembling and lasting are performed as before described, except that with the welt shown in Fig. 6 the flange 14 extends naturally inward from the welt extension to lie under the insole but with the welt shown in Fig. 7 the flange 14^a must be turned or folded inward (see 30, Fig. 7) from the welt extension so that it may be used as a lasting allowance for securing to the insole 24^a with the lining 22^a. This form of the welt is more effective in the lighter weights as used for children's shoes. An outsole 26^a may be attached by an outseam 28^a as before.

Those skilled in the manufacture of shoes will recognize that the process hereinbefore described may be varied to suit particular conditions. For example, it is within the scope of the invention to insert the short upper between the upper embracing flaps of the welt while the welt is in a flat or unformed condition and then attach the 40 welt to the upper by stitching or otherwise. Such a mode of securing is desirable for the larger and less flexible welts for work shoes and the like. Bending heavy welts on the last to angular form is facilitated by the fold scoring; in fact the 45 welt will preferably be formed-up before being solid so that after flattening out reforming on the last is easily accomplished especially as the flesh flap will stretch somewhat during the welt beating operation. It is preferable to skive the heavy- 50 ier weight uppers and tuck them well into the edge slit as shown by Figs. 4 and 6 although all shoe uppers may be skived if desired. On shoes fitted with a continuous welt the joint may be made by skiving or by butting the welt ends as 55 the manufacturer may desire, the welt ends being so cut that the joint or splice is both neat and tight.

The claims herein purposely do not embrace the shoe illustrated and described except as fitted 60 with the novel welt having an attached lasting allowance, nor do they embrace the method of manufacturing a shoe with a short upper secured to the welt between two flaps or flanges upturned from the welt extension, or such novel welt in 65 its broader aspects, all of which is claimed in a co-pending application of William C. Vizard Ser. No. 664,722 filed of even date herewith. Reference is had to that copending application for refinements in the manufacture of the welt, 70 for example skiving or thinning parts thereof for smooth or finishing contours inside or outside the shoe and to variations in the mode of securing of the welt to the short upper, all of which are equally applicable to the welt of this invention.

The nature and scope of the invention having been indicated and its preferred embodiments and the method of its manufacture and shoemaking therewith having been specifically described, what is claimed as new, is:—

5

1. In a welted shoe of the type having an insole and a short upper, grain leather weltling having one edge split producing contiguous longitudinal grain faced and flesh flaps both turned upward parallelly relative to the grain extension to embrace said short shoe upper, and also having a flange-like lasting allowance extending inward from said grain extension for securing to the insole.

2. The invention according to claim 1 in which said lasting allowance consists of a second longitudinal flesh flap at one edge of the weltling.

3. In a shoe of the type having an upper too short to overlant, a welt having a longitudinal edge-slit under one face and a second longitudinal edge-slit under the other face producing a blank having three marginal flaps, two of said flaps adjoining each other being both turned upward parallelly relative to the welt extension to embrace said short shoe upper and said remaining flap providing a flange-like lasting allowance for said short shoe upper.

4. Leather weltling split through one edge inward substantially half way through the strand forming an upper flap and a lower flesh flap both at one edge of the remaining welt extension and separable to receive a scant shoe upper between them, and also split through the opposite edge inward substantially to the inner edge of said other split forming a second flesh flap below the 35 welt extension, said latter flesh flap being bendable to lie inward from said extension and provide a flange-like lasting allowance.

5. Leather weltling according to claim 4 in which said latter edge split lies at a greater distance 40 from the upper face of the strand to preserve the thickness of the welt extension.

6. A shoe comprising an insole, a short upper the lower edge of which, in the shoe, does not extend beneath the insole, a welt having its extension turned outward from the upper and having two upstanding, integral flaps embracing said upper and a third integral flap or flange lasted flat under the insole, said upper being secured within said upstanding flaps, and a suitably se- 50 cured outsole bottoming the shoe.

7. A shoe according to claim 6 in which all three flaps are split from the same edge of the welt and said third flap extends naturally inward from said welt extension to lie under the insole.

55

8. A shoe according to claim 6 in which said two upper embracing flaps are split from one edge of the welt and said lasting allowance flange is split from its other edge but is folded inward from said welt extension to lie under the insole.

60

9. Weltling for shoes consisting of a body portion forming a welt extension, two separable flaps integral with the inner edge of said body portion and both standing substantially perpendicular to the plane of said extension, and a third 65 flap providing lasting allowance also integral with said inner edge and extending in lateral continuation of said extension.

10. The method of preparing weltling for welted shoes having short uppers which comprises cutting two edge slits in a strand of grain leather forming three integral flaps comprising one grain faced flap and two flesh flaps, and turning said grain faced flap and one flesh flap upward along a line defining the base of the slits into upper 70

75

embracing position relatively to the grain extension and leaving said third flap as free lasting allowance for the short upper.

11. The method described by claim 10 in which said two edge slits are cut in the opposite edges of the strand. 5

12. The method described by claim 10 in which said two edge slits are cut in the opposite edges of the strand and said third flap is folded to lie 10 inward of said two upwardly turned flaps.

13. The method of making shoes which includes cutting an upper too short to overlant, supplying a welt having two separable flaps at one edge of its extension and a third flap or flange 15 providing lasting allowance, attaching the lower edge of said upper between and to said two separable flaps, assembling an insole and said welted upper on a last with said lasting allowance flange at the inner side of the upper, lasting said 20 upper down to the wood while working said welt extension to the edge of the insole, setting said lasting allowance flange over the insole, securing said flange to the insole, and bottoming with an outsole secured to the welt extension outturned 25 to lie substantially in the plane of the insole.

14. The method of making shoes according to claim 13 in which said welt, after attachment to the upper, is prepared for lasting by being bent along the line of the embraced edge of the upper 30 to overturn its welt extension and to cause its lasting allowance flange to extend inward relatively to the upper.

15. The method of making shoes which in-

cludes cutting an upper too short to overlant, supplying a welt having two separable flaps at one edge of its extension and a lasting allowance flange extending inward from said welt extension, attaching the lower edge of said upper between and to said separable flaps, assembling said welted upper on a last and turning the welt extension outward forming an outturned flange at said lower edge of the upper, lasting to conform said upper to the last and said welt to 10 the shape of the last bottom and setting said lasting allowance flange inward of the upper in the plane of the welt extension, and bottoming the shoe by securing an outsole to said welt. 5

16. In a welted shoe of the type having an upper too short to overlant, a welt having an outturned welt extension provided with two separable flaps at its inner edge, said flaps being both turned upward from the welt extension and said short upper being between and secured to 20 said flaps, and said welt having a flange-like lasting allowance extending inward of the upper in lateral continuation of the welt extension.

17. A welted shoe having an upper too short to overlant, an insole within the lower edge of 25 said upper, a welt having its extension turned outward from the upper and having two up-standing flaps between which said lower edge of the upper is secured, said welt having a third flap or flange extending inward from the welt 30 extension beneath and secured to the insole, and a suitably secured outsole bottoming the shoe.
